Specification of Letters Patent.

Patented Oct. 13, 1914.

Application filed November 8, 1913. Serial No. 799,886.

To all whom it may concern:

Be it known that I, GEORGE W. BERNAUER, a citizen of the United States, residing at St. Charles, county of St. Charles, State of Missouri, have invented a new and useful Press, of which the following is a specification.

This invention relates to improvements in presses especially designed for, but not necessarily restricted to, the cementing of shoe-soles and, among others, has for an object the provision of a simple, compact, inexpensive and efficient machine of the character described which possesses great and unusual power of compression.

Other objects and advantages may be noted in the following parts of this specification and the appended claims.

In the accompanying drawings, in which like numerals refer to like parts throughout, Figure 1 is a front elevation, partly in section, of the press, and Fig. 2 a side elevation thereof.

Referring to the drawing numeral 1 denotes a stationary table or platform which may be rigidly supported in position by braces or legs extending to the floor or in any other manner desired. Secured upon the upper surface of said table is a metal casting 2 provided with sockets 3 at its opposite ends into which project set-screws 4. Disposed in sockets 3 are the free extremities of shafts 5 whose opposite ends are detachably connected by cross-head 6 having set-screws 7 for its vertical adjustment relative to said shafts. Disposed between casting 2 and cross-head 6 are presser-plates 8, 8^a having oppositely inclined under surfaces 9 and 10, said plates being apertured at 11 for the passage of shafts 5 and retained in spaced relation by helical springs 12 mounted on said shafts. Projecting centrally through members 1, 2, 8 and 8^a is a rod 13 whose upper extremity is connected with plate 8 and whose lower end is pivotally secured as at 14 to a treadle-lever 15 hingedly supported at 16 upon a standard 17, said rod being preferably in two parts coupled by member 13^a. The forward portion of said lever is provided with a foot rest 18 and a rigid pawl 19, the latter adapted to engage the teeth of a ratchet 20 pivotally secured at 21 to a standard 22. It will be noted that the upper end of said ratchet is slotted as at 23 and is normally held in engagement with pawl 19 through

the agency of spring 24 connected with standard 22 as at 25 and in actual practice the connection between lever 15 and standard 17 is sufficiently loose to allow of slight lateral movement of said lever to permit of the disengagement of the pawl and ratchet. Mounted upon rod 13 and engaging threads 13^b thereof is a hand-wheel 26 having a thickened hub 27 and it is obvious that upon upward rotation of said wheel the hub will eventually contact with collar 2^a of casting 2.

Aside from the important fact that all the parts of this press are readily detachable so that repairs and replacements can be easily effected, a further valuable advantage lies in the fact that its capacity may be increased or diminished to any desired extent simply by increasing or diminishing the length of shafts 5 and springs 12 and adjustment of coupling 13^a which, of course, may be considerably longer than shown in the drawing.

In the manufacture of certain kinds of shoes it becomes necessary to glue or cement what is known as a "tap-piece" to the inner surface of a sole and in order that the advantages of certain features of this machine may be fully appreciated it should be explained that the shank end of said "tap-piece" is skived. Hence, when a number of soles thus composed are placed one upon another with the toe portions all in register it follows that such a stack will incline toward the rear or shank portion and that, therefore, a machine which will effectually compress the cemented parts throughout their entire length should embrace devices designed with special references to this inclination of a number of superposed soles.

In operation, a number of soles and "tap-pieces", having been joined with cement, are superposed and placed upon the upper surface of plate 8^a, whereupon the operator depresses lever 15 which serves to bring presser-plate 8 down upon the stack. In this position said plate is maintained through the agency of pawl 19 and ratchet 20 while another batch of soles is made ready for the press. The second batch being ready, the pawl and ratchet are disengaged, the presser-plates are raised by springs 12 and the freshly cemented parts are disposed upon the upper surface of casting 2, whereupon lever 15 is again depressed to bring the presser-plates down upon the

soles. When the operator has forced lever 15 downward as far as possible through the agency of his own weight, he locks it in position by means of pawl 19 and ratchet 20 5 and then brings hub 27 of wheel 26 to bear against collar 2^a of casting 2. Obviously, further revolution of said wheel has the effect of further depressing plates 8, 8^a so that extraordinary pressure is exerted upon 10 the soles and it should here be noted that, despite the inclination present in the stacks of soles, as before mentioned, the pressure thereupon is evenly distributed by reason of the corresponding inclination of the under 15 surfaces of said plates as shown at 9 and 10.

What I claim as new and desire to secure by Letters-Patent is:—

1. A machine of the character described comprising pressing-plates, means for forcing the same into engagement with the articles to be pressed, mechanism for increasing the pressure of said plates in supplement to said means, and members adapted to separate said plates and articles after operation 25 of said means and mechanism.

2. A machine of the character described comprising pressing-plates, means for forcing the same into engagement with the articles to be pressed, devices for locking said 30 means, and mechanism for increasing the pressure of said plates in supplement to said means.

3. A machine of the character described comprising pressing-plates, means for forcing the same into engagement with the articles to be pressed, devices for locking said 35 means, mechanism for increasing the pressure of said plates in supplement to said means, and members adapted to separate said plates and articles after operation of 40 said means and mechanism.

4. A machine of the character described comprising a stationary member, a rod projecting therethrough, a pressing-plate secured to said rod, threads upon said rod extending substantially above and below said 45 member, a lever connected with said rod

adapted to force said plate into engagement with the article to be pressed, and a wheel 50 freely engaging said threads adapted to bear against said member, whereby the pressure of said plate may be increased.

5. A machine of the character described comprising a stationary member, a rod projecting therethrough, a pressing-plate secured to said rod, threads upon said rod 55 extending substantially above and below said member, a lever connected with said rod adapted to force said plate into engagement with the article to be pressed, devices 60 for locking said lever, and a wheel freely engaging said threads adapted to bear against said member, whereby the pressure of said plate may be increased.

6. A machine of the character described 65 comprising a stationary member, a rod projecting therethrough, a pressing-plate secured to said rod, threads upon said rod extending substantially above and below said member, a lever connected with said rod 70 adapted to force said plate into engagement with the article to be pressed, a wheel freely engaging said threads adapted to bear against said member, whereby the pressure of said plate may be increased, and means 75 for automatically lifting said plate from said article.

7. A machine of the character described comprising a stationary member, a rod projecting therethrough, a pressing-plate secured to said rod, threads upon said rod extending substantially above and below said member, a lever connected with said rod 80 adapted to force said plate into engagement with the article to be pressed, devices for 85 locking said lever, a wheel freely engaging said threads adapted to bear against said member, whereby the pressure of said plate may be increased, and means for automatically lifting said plate from said article.

GEORGE W. BERNAUER.
